UNITED STATES PATENT OFFICE.

JESSE F. MITCHELL, OF CHICAGO, ILLINOIS.

SAFETY CHAIN CLASP.

Application filed January 2, 1925. Serial No. 250.

To all whom it may concern:

Be it known that I, JESSE F. MITCHELL, a citizen of the United States, and a resident of Chicago, in the county of Cook and State 5 of Illinois, have invented a new and useful Improvement in Safety Chain Clasps, of which the following is a full, clear, and exact description.

My invention relates to improvements in 10 safety chain clasps, and more particularly to that type of clasp intended for use with necklaces, lavallières, and the like, and it consists in the combinations, constructions and arrangements herein described and 15 claimed.

An object of my invention is to provide 20 a clasp of the character described in which the cooperating members of the clasp may not be disengaged without first compressing a portion of one of the members.

A further object of my invention is to 25 provide a clasp of the character described in which novel means is provided for facilitating the engagement of the cooperating members of the clasp and by means of which operative engagement of the members may be performed by feeling the members, thus permitting actuation of the clasp in the dark or behind the neck of the wearer.

30 A further object of my invention is to provide a clasp of the character described which is extremely light in construction and which is ornamental in appearance.

Other objects and advantages will appear 35 in the following specification, and the novel features of the invention will be particularly pointed out in the appended claims.

My invention is illustrated in the accompanying drawings forming part of this application, in which

40 Figure 1 is a view of an embodiment of my invention,

Figure 2 is a view of the device shown in Figure 1 with the clasp member partially 45 disengaged, and

Figure 3 is a side elevation of the device shown in Figure 1.

In carrying out my invention I make 50 use of an ornamental chain or necklace 1 terminating at each end in an ornamental metal ring 2 and 3 respectively.

The ring 2 forms one of the cooperating members of my improved clasp.

The principal cooperating member is 55 shown at 4 and is substantially in the shape of a figure 8, having one of its loops

greater than the remaining one. The loop 5 which is the smaller of the two is for the purpose of receiving the ring 3 as shown in Figure 1.

The member 4 is constructed of a single piece of stiff resilient metal wire, one end 6 of which is curved inwardly and terminates at the upper end of the larger of the loops of the figure 8. The opposite end 7 is substantially S-shaped in contour (see Figure 1) and terminates at 8 adjacent to that end of the larger loop nearest to the loop 5. There is sufficient clearance normally between the end 8 and the adjacent portion of the member 4 to permit the passage of the ring 2 thereby.

It will be noted that the larger of the loops of the member 4 is substantially pear-shaped. This is for the purpose of normally 75 guiding the ring 2 to the position shown in Figure 1 when the chain or the necklace 1 is about the neck of the wearer, and thus holding the ring 2 at a point removed from the S-shaped portion 7 of the member 4.

From the foregoing description of the various parts of the device the operation thereof may be readily understood. In removing the ring 2 from engagement with the member 4, the wearer moves the ring 2 80 in the direction of the arrow 9 (see Figure 1). Continued movement of the ring 2 in this direction will cause the S-shaped member 7 to be flexed toward the adjacent portions of the member 4 as shown in Figure 2. 85 It will be noted that to move the ring to the position shown in Figure 2 certain force must be applied to overcome the resistance offered by the member 7. The ring 2 may then be passed between the end 8 and the adjacent portion of the member 4 and moved upwardly in a direction opposite to the arrow 9, and finally over the portion 6 and entirely out of engagement with the member 4.

To disengage the cooperating members 2 and 4 the steps just described are reversed, i. e., the ring 2 is moved over the end 6 and downwardly, as viewed in Figure 1, beyond the end 8 and thence up over the portion 7 105 to the position shown in Figure 1.

It will be noted that the contour and position of the end 6 permits engagement of the ring 2 with the member 4 without the necessity of closely watching the members. 110 Thus the members may be initially engaged behind the neck of the wearer by determin-

ing the position of the members by touch. After the clasp has been used a few times, the wearer may quickly disengage and engage the members 2, ascertaining their relative positions entirely by feeling the members.

I claim:

1. A safety chain clasp of the character described comprising a pair of cooperating members, one of said members having a loop portion fashioned to receive the remaining member, one end of said loop portion being fashioned to prevent the unintentional disengagement of its complementary cooperating member, the opposite end being projected inwardly of the loop for facilitating the engagement of said complementary cooperating member therewith.
2. A safety chain clasp of the character described comprising a pair of cooperating

members, one of said members being substantially in the shape of a figure 8 each of said members being arranged for connection with the opposite ends of a necklace chain or the like, and means associated with said members for preventing the unintentional disengagement thereof.

3. A safety chain clasp of the character described comprising a pair of cooperating members, one of said members being substantially in the shape of a figure 8 each of said members being arranged for connection with the opposite ends of a necklace chain or the like, means associated with said members for preventing the unintentional disengagement thereof, and other means associated with one of said members for facilitating the engagement of its cooperating member therewith.

JESSE F. MITCHELL.
